UNITED STATES PATENT OFFICE.

CHARLES B. SCHROEDER, OF CHICAGO, ILLINOIS, ASSIGNOR TO EDERHEIMER, STEIN COMPANY, OF CHICAGO, ILLINOIS, A CORPORATION OF DELAWARE.

POCKET CONSTRUCTION FOR GARMENTS.

1,203,057.

Specification of Letters Patent. Patented Oct. 31, 1916.

Application filed May 5, 1915. Serial No. 25,913.

To all whom it may concern:

Be it known that I, CHARLES B. SCHROEDER, a citizen of the United States of America, and a resident of Chicago, county of Cook, and 5 State of Illinois, have invented certain new and useful Improvements in Pocket Construction for Garments, of which the following is a specification.

The main objects of this invention are to 10 provide an improved design and arrangement of a pocket for garments, which permits of being made more spacious than the ordinary pocket, and which is capable of conveniently accommodating larger articles 15 than can be placed in the pockets of usual construction; and to provide a patch pocket construction of this kind artistically arranged on the garment so as to enhance the appearance thereof.

20 An illustrative embodiment of this invention is shown in the accompanying drawings, in which—

Figure 1 shows a boy's reefer having a patch pocket of this kind arranged thereon. 25 Fig. 2 is a sectional view of the garment taken on the line 2—2 of Fig. 1. Fig. 3 is a similar view taken on the line 3—3 of Fig. 1.

The pocket is of the type known as patch pockets where a piece of cloth of the desired 30 shape is stitched onto the exterior of the garment to form the pocket. In the particular construction herein shown, the patch 1 is of oblong shape and is attached on the front part of the garment so that it is almost 35 entirely forward of the sleeve, and extends from the arm-hole to a point considerably below the end of the sleeve 2. The front edge 3 of the patch is substantially straight and parallel with the front edge 4 of the 40 coat. This rounds off at 5 toward the top, which is cut in at 6 to fit around the arm. The rear edge 7 is substantially parallel to the front edge of the patch for a distance of 45 between one-third and one-half way up the length of the patch, and above that is cut in at 8 to provide the pocket opening. The 50 stitches 9 securing the patch extend along the top, front and bottom edges and along the parallel part of the rear edge.

55 If desired, the utility of the garment may be increased by securing a patch 10 of conventional pocket shape upon the patch 1 near the upper end, which constitutes a breast pocket for the reception of small articles.

55 Also the appearance of the construction may

be improved by applying a patch 11 to the patch 1 on a line with the terminus of the stitches along the rear edge. The shape of this patch is made so as to resemble a pocket flap, and is stitched around all of the edges, 60 whereby it gives the appearance that the lower part of the patch 1 constitutes a pocket of the usual construction. This arrangement of a patch pocket provides a garment which at first glance does not differ materially from 65 the conventional construction of coats and arrangement of pockets. However, such a large and spacious pocket makes it possible for articles of considerable length to be placed therein, which could not be done in 70 pockets of the usual construction. This is of particular advantage to boys and youths who desire to have a coat in which they can carry their skates and at the same time, if desired, place their hands.

75 Although but one specific embodiment of this invention has been herein shown and described, it will be understood that some of the details of the construction shown may be altered or omitted without departing from 80 the spirit of this invention as defined by the following claims.

I claim:

1. A coat having secured to the outside of the front portion, an overlapping pocket 85 member extending downwardly from the arm-hole to a point adjacent the lower end of the coat sleeve, and extending forwardly to a point inward from the front edge of said portion, and being attached to the body of 90 the coat along its front, bottom and rear edges, except along the rear edge from a point adjacent the arm-hole to an intermediate point thereof to constitute an entrance opening for the pocket formed between said member and the coat body, the 95 rear edge of said pocket member being covered by the coat sleeve when in normal position.

2. A coat having a piece of material secured to the outside of the front thereof in advance of a median vertical line through the arm-hole to which the usual sleeve is attached, said material being secured to the coat along its front and bottom edges and the 100 lower portion of its rear edge, thereby defining a pocket with an entrance opening adjacent the arm-hole, and said piece of material being of a length substantially equal to the 105 length of the sleeve.

3. A coat having a piece of material secured to the outside of the front thereof in advance of a median vertical line through the arm-hole, to which the usual sleeve is attached, said material being secured to the coat along its front and bottom edges and the lower portion of its rear edge, thereby defining a pocket with an entrance opening adjacent the arm-hole, said piece of material being of a length substantially equal to the

length of the sleeve, and a flap secured to the outer side of said material with its upper edge substantially in alignment with the bottom of said opening.

Signed at Chicago this 3d day of May, 1915.

CHARLES B. SCHROEDER.
